P. M. HOTCHKIN,
LEG ATTACHMENT FOR FORMS.
APPLICATION FILED DEC. 31, 1917.

1,318,758.

Patented Oct. 14, 1919.

THE COLUMBIA PLANOGRAPH CO., WASHINGTON, D. C.

UNITED STATES PATENT OFFICE.

PAUL M. HOTCHKIN, OF CHICAGO, ILLINOIS, ASSIGNOR TO CURTIS-LEGER FIXTURE CO.,
A CORPORATION OF ILLINOIS.

LEG ATTACHMENT FOR FORMS.

1,318,758.

Specification of Letters Patent.

Patented Oct. 14, 1919.

Application filed December 31, 1917. Serial No. 209,674.

To all whom it may concern:

Be it known that I, PAUL M. HOTCHKIN, a citizen of the United States, residing at Chicago, in the county of Cook and State 5 of Illinois, have invented a certain new and useful Improvement in Leg Attachments for Forms, of which the following is a specification.

My invention relates to that class of devices which are designed to be used in show windows and similar locations for displaying articles of wearing apparel.

Up to the present time, devices of this class, with which I am familiar, are formed 15 of papier mâché, or wood, the use of which gives rise to a number of objections, among which might be named sensitiveness to atmospheric changes, and after being in use a short time, they crack or peel. These 20 materials cannot be modeled from the human form and consequently do not display garments, hosiery and similar articles as satisfactorily as if true to nature.

Continued use of the figure frequently results in the breaking of the toes or heels and most of the devices require a brace to support them when in use.

My invention has for its object to provide a form of construction which will avoid 30 all of the objectionable features possessed by the papier mâché and wood forms, and which will stand erect without the interpolation of a brace or other supporting device, and to have all the grace of outline of the 35 human form hitherto unattainable.

My means for accomplishing the foregoing objects may be more readily understood by having reference to the accompanying drawings, which are hereunto annexed and 40 are a part of this specification, in which:

The figure is a view of my improvement secured to a papier mâché body form, the legs being shown in section to show the interior construction.

Similar reference numerals refer to similar parts throughout the entire description.

As shown in the drawings, the attachment 50 comprises a metal last which forms the heel, sole and toes of the foot of the figure, combined with a reinforced composition molded in a cast copied from a natural form.

The metal last is formed with a sole 4, and hollow toes 5. A rib 2 runs along the center of the sole 4 and terminates in a boss

7 which is provided with a central opening 55 in which is mounted a tube or pipe 8 which extends upwardly to a metal yoke 9. The sole 2 is cast or formed with a wall which forms the heel 3, there being a space intermediate the boss 7 and this wall to be filled 60 with the composition.

This yoke 9, is formed of a pair of arms 11 and 12, which terminate in bosses 13 and 14, which are provided with longitudinal openings therethrough in which are mounted the upper end 15 of the pipe 8. A set screw 16, is provided to regulate the length 65 of the pipe intermediate the yoke 9, and the last 2, by which is determined the length of the leg, which is to be constructed. 70

In the central portion of the yoke 9, is mounted a rod or pipe 17, which is secured to a brace 18, generally formed of wood and mounted inside of the papier mâché body. A collar 20 is provided in order to adjust 75 the length of the rod 17. When the mold has been formed, the last, rods and yoke, are placed therein and the composition 21, is cast around it, filling up the spaces in the last and entirely surrounding the pipes or 80 tubes 8. This composition is preferably formed of plaster of Paris which has mixed with it, a fiber stiffening made from fragments of either hemp, rope, hair, burlap, string, etc., in sufficient quantities to give it 85 strength. The composition is then mixed with water until sufficiently plastic to be poured into the mold.

The result of this construction is obvious. It is impossible to break the toes or heels of 90 the figure owing to the presence of the metal last while its weight is sufficient to support the figure in an upright position without the assistance of a standard or other supporting means. 95

The tubes or rods 8, impart sufficient rigidity to the composition to make it very durable while the composition assumes the form of the cast made from nature since the last is sufficiently small to be placed inside 100 of the mold of the foot in the same manner as a core is placed in a mold, it is obvious it will not vary the shape of the exterior of the composition, and inasmuch as the composition is not materially affected by 105 changes of temperature, it can be used for an indefinite period without deteriorating.

Having described my invention what I re-

gard as new and desire to secure by Letters Patent of the United States is:

1. A leg attachment for forms, comprising a metal last, forming a wall for the heel, sole and toes of the foot, a boss cast or formed inside the wall of the heel, a tube mounted therein, there being a space intermediate the boss and the wall of the heel, a yoke, the upper end of said tube being secured to one side of said yoke, means to regulate the spaced relationship of said yoke to said last, and composition which surrounds said tubes and fills in the spaces in the last and forms the legs.
- 15 2. A pair of legs for a form comprising the combination of composition adapted to reproduce the natural form, an upwardly extending tube for each leg, a yoke mounted on the upper end of each tube, a metal last, forming a wall for the heel, sole and toes of each foot, one of said lasts being secured to the lower end of each tube, said composition being cast around said tubes and filling the spaces in said lasts and forming the legs.
- 20 3. A pair of legs for a form comprising the combination of composition adapted to reproduce the natural form, an upwardly extending tube for each leg, a yoke mounted on the upper end of each tube, a metal last formed with a sole, a wall at one end of said sole which forms the heel and at the other end which forms the toes, a rib which connects the two, one of said lasts being secured to the lower end of each tube, said composition being cast around said tubes and filling the spaces in said lasts, and forming the legs, and means to adjust the position of said yoke.
- 25 4. A leg attachment for forms each leg of

which is provided with a metal last forming the heel, sole and toes of the foot, a boss cast or formed in the heel, a tube mounted therein, a yoke having a pair of arms which terminate in bosses, having openings therein, the upper end of said tubes being mounted in said openings, set screws in said bosses which engage said tubes, an upwardly extending rod mounted in the central portion of said yoke adapted to engage the top portion of a form, and means to adjust the length of said rod.

5. A leg attachment for forms, comprising a foot means contained in foot to hold said form upright without an exterior support, a boss cast or formed in the heel, a tube mounted therein, a yoke having a pair of arms which terminate in bosses, having openings therein, the upper end of said tubes being mounted in said openings, set screws in said bosses which engage said tubes, an upwardly extending rod mounted in the central portion of said yoke adapted to engage the top portion of a form, and means to adjust the length of said rod.

6. A pair of legs for a form comprising the combination of composition adapted to reproduce the natural form, an upwardly extending tube for each leg, a yoke mounted on the upper end of each tube, a last secured to the lower end of each tube, said last being smaller than the size of the foot to be molded and having hollow toes and heel, said composition being cast around said tubes and filling the spaces in said lasts and forming the legs, and means to adjust the position of said yoke.

In testimony whereof, I have signed the foregoing specification.

PAUL M. HOTCHKIN.
